UNITED STATES PATENT OFFICE.

JOHN O. KEEFOVER, OF TULSA, OKLAHOMA.

WALKING BEAM.

Application filed August 3, 1925. Serial No. 47,963.

To all whom it may concern:

Be it known that I, JOHN O. KEEFOVER, a citizen of the United States, and resident of Tulsa, in the county of Tulsa and State 5 of Oklahoma, have invented certain new and useful Improvements in Walking Beams, of which the following is a specification.

This invention relates to improvements in 10 well rigging, particularly to improvements in walking beams, and it consists of the construction, combinations and arrangements herein described and claimed.

An object of the invention is to adapt the 15 walking beam of an oil well rigging to the purpose of operating a pump, the particular improvement residing in the provision of an auxiliary walking beam which rides upon the main walking beam and operates in 20 such a manner as to increase the stroke of the pump and thereby increase the output of the well without requiring the application of increased power to the main walking beam.

25 Other objects and advantages will be apparent from the following specification, reference being had to the accompanying drawing, in which—

Figure 1 is a side elevation of a walking 30 beam and some of the associated mechanism and showing the auxiliary walking beam in position.

Figure 2 is a detail perspective view 35 through a portion of the main walking beam, again showing the auxiliary walking beam.

It is not an uncommon practice to extract 40 oil from a well by pumping. The necessity for pumping arises when the oil has lost its pressure so that it fails to rise to the surface. It is also quite common to employ 45 the customary walking beam of an ordinary well rigging as the actuating member of the pump.

In Figures 1 and 2 the main walking 50 beam 1 is journaled at 2 upon the fixed standard 3. The main walking beam is rocked upon its journal by the crank of the bull wheel 5 through the connecting rod 6. The oil well rigging includes a main sill 7.

55 Mounted upon the free extremity of the main walking beam 1 is the auxiliary walking beam 8. This walking beam has a trunnion 9 which rests in and rocks upon a saddle 10 suitably affixed to the main walking beam. The extremities of the auxiliary walking beam carry iron plates which are

appropriately bent to form yokes 11 and 12, the purpose of which is to prevent cutting of the wire ropes 13 and 14 the bights of which are applied thereto. 60

The wire rope or other flexible member 13 is fixed at 15 to the main sill 7 and performs the function of restraining the auxiliary walking beam 8 upon rocking of the main walking beam 1. It includes a 65 turn buckle 16 by means of which necessary adjustments can be made. The wire rope 14 is that of a pump rod 17 which operates in the cylinder 18.

The operation is readily understood. In 70 Figure 1 the main walking beam 1 is shown in full lines as occupying the intermediate position in respect to the range of its rocking motion. If the pump rope 14 were suspended from the free extremity of the main 75 walking beam 1 the amount of throw or reciprocation would be no greater than the amount of movement represented between the dotted line positions *a* and *b* of the main walking beam. 80

Assume that the free end of the crank 4 reaches the upper extremity *c* of its movement. The main walking beam 1 will assume the position *a*. The trunnion 9 of the auxiliary beam 8 will assume the position *d*. 85 The weight of the rope 14 and the pumping apparatus suspended therefrom will bring the point of application of the rope to the point *e*, the opposite end of the auxiliary beam being restrained by the rope 13. 90

Upon the next half revolution of the bull wheel 5 the pin of the crank 4 will assume the position *f*, whereupon the main walking beam 1 assumes the position *b*. The trunnion 9 is lifted to the position *g* causing independent rocking of the auxiliary beam 8 so that the point of application of the pump rope 14 assumes the position *h*. The opposite extremity of the auxiliary beam is again restrained by the rope 13. 100 It is readily seen that the distance between the points *e* and *h* is considerably greater than the distance between the dotted line positions of the walking beam 1 at the right extremity. The action of the auxiliary 105 walking beam 8 increases the amplitude of reciprocation of the pump rod and in actual tests has been demonstrated to increase the output of the well. A well that formerly delivered 5 barrels of oil in a given time was 110 made to yield 8 barrels in the same time by use of the auxiliary walking beam without

requiring the application of any appreciable increase of power.

The percentage of water withdrawn with the oil has also been shown to be less. The

5 barrels of oil mentioned contained a certain percentage of water, but by keeping up the action of the pump by means of the auxiliary walking beam the result is to withdraw more oil and not so much water. It
10 is readily seen that the principle of the invention is to provide a constantly operable auxiliary walking beam, one end of which carries the pumping apparatus, the other end being suitably anchored to a fixture that
15 is independent of the main walking beam. The action is as stated: A marked increase in the range of reciprocation of the pump cable or rope.

While the construction and arrangement
20 of the improved walking beam is that of a generally preferred form, obviously modifications and changes may be made without departing from the spirit of the invention or the scope of the claims.

25 I claim:—

1. In combination with a main walking beam and pump rod, an auxiliary walking beam rockably mounted above and upon the main walking beam, means connecting one
30 extremity of the auxiliary walking beam with the pump rod, and means to restrain the opposite end of the auxiliary walking beam producing an independent rocking motion of the auxiliary walking beam on rocking
35 of the main walking beam and causing reciprocation of the pump rod, said means

consisting of a flexible member having one end attached to the opposite end of the auxiliary walking beam and the other end to a fixture.

2. In combination with a main walking beam and pump rod, a trunnion located at one extremity of said walking beam, an auxiliary walking beam mounted above the main walking beam and upon said trunnion, means including a cable connecting one extremity of the auxiliary walking beam with the pump rod, and anchoring means including a flexible member in connection with the opposite extremity of the auxiliary walking beam restraining such extremity upon rocking motion of the main walking beam, and producing an independent rocking motion of the auxiliary walking beam.

3. The combination of a main walking beam, an auxiliary walking beam, means by which the auxiliary walking beam is journaled upon one extremity of the main walking beam, anchoring means including a cable and an adjustable turn buckle for restraining one end of the auxiliary walking beam to produce an independent rocking motion of the auxiliary walking beam when the main walking beam rocks, a cable for connecting the opposite extremity of the auxiliary walking beam with a pump rod, and means including a metallic yoke interposed between each of the two cables and the extremities of the auxiliary walking beams to protect the latter.

JOHN O. KEEFOVER.
